OTHER PUBLICATIONS

Co-pending U.S. Appl. No. 29/731,995, filed Apr. 20, 2020, entitled Display Unit.

Primary Examiner — Kevin K Rudzinski

Assistant Examiner — Paul D Bohannon

(74) *Attorney, Agent, or Firm* — Gerard J. McGowan, Jr.

(57) **CLAIM**

The ornamental design for display unit, as shown and described.

DESCRIPTION

FIG. 1 is a perspective view of a first embodiment of our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of another embodiment of our new design;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The broken lines shown in the drawings are for the purpose of illustrating portions of the article and form no part of the claimed design.

1 Claim, 10 Drawing Sheets
